ABSTRACT OF THE DISCLOSURE

A sheet conveying system for carrying sheet material from a delivery station to a discharge station having a rod rotatably mounted for engagement with spring stock wherein the sheet material is secured between the rod and sheet material for positive gripping.

This invention relates to sheet conveyer systems and, in particular, to an improved sheet gripper mechanism that is adapted for use in xerographic reproducing machines or comparable types of devices.

One type of conveyer mechanism employed in xerographic reproducing apparatus for conveying sheet support material from a receiving station into transfer contact with a xerographic surface and then to delivery station is disclosed in Pat. No. 3,071,370 issued Jan. 1, 1963 to Robert A. Hunt and Gordon P. Taillie.

In this type of conveyer a gripper mechanism is used to transport a sheet material through a predetermined path. Positive action of the gripper mechanism and accurate alignment of a chain drive carrying the gripper mechanism are necessary to insure proper alignment of sheet material with a developed powder image on a xerographic drum as the sheet is moved through the path of travel. Further, the sheet should be transported in a position parallel to the direction of movement thereof in order to provide proper registration and effective contact with the xerographic drum. The gripper mechanism is transported to the xerographic drum where the sheet material is moved into contact with the drum by a lifting mechanism.

The gripper mechanism is actuated to a closed position at the receiving station to positively grip the sheet material. The gripper mechanism is then conveyed to a xerographic plate in the form of a drum where the sheet is moved into contact therewith by a paper lifting mechanism. The forward movement of the gripper actuates the lifting mechanism as the same moves past the xerographic drum. The gripper is then conveyed to the releasing station where the gripper is opened and the sheet material released. The sheet should be conveyed in a path substantially in parallel with the path of movement of the conveyer to prevent any flutter thereof and to assist the lifting mechanism in maintaining the sheet material in contact with the xerographic drum.

Therefore, it is an object of this invention to improve sheet gripping mechanisms.

A further object of this invention is to improve sheet gripping mechanisms to transport sheet material in a direction parallel to the direction of movement thereof.

Yet another object of this invention is to improve sheet conveying systems.

Yet another object of this invention is to eliminate gripping marks, and lead edge crimping.

Another object of this invention is to simplify the opening and closing of sheet grippers.

2

A still further object is to improve stacking capabilities by keeping the sheet material flat.

These and other objects of the invention are attained by a sheet conveying system for carrying sheet material from a delivery station to a discharge station having a rod rotatably mounted for engagement with spring stock wherein the sheet material is secured between the rod and sheet material for positive gripping.

For a better understanding of the invention as well as other objects and further features thereof, reference is had to the following detailed description of the invention to be read in connection with the accompanying drawings, wherein:

FIG. 1 illustrates schematically a preferred embodiment of the invention in a xerographic apparatus;

FIG. 2 is a top view of the paper gripper mechanism shown with the gripper in open position;

FIG. 3 is a front view of the paper gripper mechanism shown in FIG. 2 with the gripper in an open position;

FIG. 4 is an enlarged section view of the gripper mechanism taken along line 4—4 of FIG. 2;

FIG. 5 is a section view taken along line 5—5 of FIG. 1;

FIG. 6 is a top view of the paper lift mechanism.

Referring now to FIG. 1, there is shown a continuous xerographic reproduction machine containing the preferred embodiment of the present invention. The machine is of the type disclosed in the above-mentioned patent to Hunt et al. The xerographic apparatus comprises a xerographic drum 20 which rotates in the direction indicated by the arrow to cause the drum surface sequentially to pass a plurality of xerographic processing stations.

For the purpose of the present disclosure, several xerographic processing stations in the path of movement on the surface may be described functionally, as follows:

A charging station at which a uniform electrostatic charge is deposited on the photoconductive layer of the xerographic drum is shown at A. An exposure station at which an image is projected onto the drum surface and a light to dissipate the drum charge on the exposed areas thereof, and thereby form a latent electrostatic image on the copy to be reproduced is shown at B. A developing station, where a xerographic drum is developed is shown at C. A transfer station at which the xerographic powder image is electrostatically transferred from the drum surface to the material is shown at D. A drum cleaning and discharge station is shown at E.

In the embodiment shown in FIGS. 1 and 2, the sheet feeding mechanism includes a chain conveyer 26 which moves in a direction 28 carrying one or more paper gripper mechanisms 30 in a circuit between sheet feeding station 32 and a sheet delivery station 34. Means are provided to activate the grippers to cause the grippers to take hold of the front edge of a sheet of support material 36 inserted into the machine at the station 32 and to hold the sheet while traveling to the delivery station and to release the sheet for removal from the machine. In the embodiment shown, a sheet of transfer material is fed manually by an operator to the paper gripper 30 and is forwarded by the paper gripper into contact with the xerographic drum 20 at image transfer station D.

As the paper gripper is advanced by the chain conveyor, it strips the transfer material from the drum and transports it to a fixing device, such as a heat fuser 38 where the xerographic powder images previously transferred to the support surface are permanently fixed thereto.

Operation of a paper conveyor is effected by actuation of a limit switch 1-LS, upon insertion of the sheet transfer material 36 into the paper gripper 30 at the sheet feeding station 32.

Referring in particular to FIGS. 2, 3, 4 and 5 the conveyor includes a pair of endless roller chains 26, one on each side of the machine, which passes from sprocket 62 carried by axle 64 over sprockets 66 and 68 carried by axles 70 and 72, respectively. The axle 70 has a paper lift mechanism 75 mounted thereon to be described below. Sprockets 66 and 68 guide the chain in a path tangential to the surface of the drum. The chain is then carried over and around a second sprocket 74 on axle 76 down to sprocket 78 secured to drive shaft 55 and then back to the sprocket 62 and axle 64.

Therefore, it is understood that each set of sprockets are positioned on their respective shafts or axles to space the chains apart from each other by a distance greater than the length of the drum. The chains 26 carry two paper grippers 30 which are spaced equally from each other along the length of the chain. The paper grippers are positioned on the chain at right angles to the path of travel of the chain for movement therewith and in a circuit between the sheet feeding and sheet delivery stations.

After fusing, the finished copy is discharged from the apparatus at the sheet delivery station 34.

The paper gripper 30 includes side frame members 80 which are secured to the chain conveyor 26.

A rear frame member 82 connects the side frame members 80 and is mounted therebetween. Attached to the rear frame member 82 and extending along the top of the paper gripper 30 is a longitudinal strip of spring stock 84 formed with cut out portions 86 along the front portion thereof. Extending to the front portion of the side frame members 80 is the body 88 in the form of a piece of rigid material. Mounted for rotation within the body 88 is a rod 90 which can be moved in an arc of approximately 90° are camming elements 92 attached to either end of rod 90. The rod 90 is formed with an opening 94 therein as shown in FIGS. 2 and 3.

The body 88 is formed with openings 89 therein. The cut out portions 86 of the openings stock 84 are positioned above these openings 89. A paper lead edge control guide 91 is mounted within each opening 89 and is secured by a pin 93 which fits into an opening 95 in the guide 91 and an opening 97 in the body 88. A leaf spring 99 is positioned between the rear portion of the body 88 and the rear portion of the spring stock 84 to maintain the lead edge guide in contact with the rod 90.

A sheet material may thus be inserted at the sheet delivery station 32 and placed within the slot 94 of the rod 90. As the sheet material is inserted through the guides at the delivery station 32 the limit switch 1-LS is actuated through an appropriate circuit, not shown, which includes a several second time delay. The sheet material is inserted into the slot 94 and after the appropriate time lapse, the solenoid SOL-1 is actuated and serves to move the lever 96 in the direction by the arrow as shown in FIG. 1. The lever 96 thus moves the cam actuator 102 which is moved pivotally about a shaft 104. The cam actuator 102 moves the cam 92 in a clockwise direction as shown in FIG. 1 thus moving the rod 90 in a clockwise direction as shown in FIG. 4 to positively grip the sheet material between the upper surface 106 of the rod 90 and the under surface of the extending portions 108 of the longitudinal spring stock 84. The lead edge of the support material a paper is guided by the guide 91 and moved into a position to be gripped by the edge 107 of the opening 94 in the rod 90. The machine is then operable in the normal manner through the suitable circuit to move the gripper bar from the sheet delivery station 32 by means of the chain conveyor 26 to the sheet transfer station D.

As the gripper 30 is moved by the chain conveyor 26 and approaches the drum 20, the paper lift mechanism 110 support on the idler shaft 111 is actuated. The lead-

ing edge of the gripper 30 contacts the lever 112 which pivots about the pin 114 and moves the lever forward. The arms 116 and 118 are moved downward by the lever 112 and rotate the paper lift support 120 counterclockwise. The support 120 is pivotally mounted on the brackets 121 which are secured to the shaft 111. Thus, as the gripper 30 passes the paper lift mechanism 110 the paper lift support 120 is moved below the path of movement of the gripper. After the gripper 30 passes the paper lift mechanism and releases the lever 112 the paper lift support is returned to its normal position as shown in FIG. 1 by a pair of return springs 112 secured to the brackets 121 shown in FIG. 7. The support 120 returns to its normal position in a rapid manner aided by the spring 122 to lift the support material carried by the gripper into intimate contact with the drum 20 to eliminate any lead edge deleterious and maintain contact between the support material and the drum. The gripper is then transported to the delivery station. To accomplish the discharge of the sheet material there is provided a pair of delivery rollers 140 and 142. Delivery roll 140 is an idler roll journaled for rotation in the frame 141 of the xerographic machine. Delivery roll 142 is driven by a sprocket 144 driven by the chain conveyor 26. The sprocket 144 drives a gear 146 through the shaft 148 to which the gear 146 is keyed. The gear 146 in turn drives the driven delivery roller 142, which is keyed to gear 197. The idler delivery roll 140 has an O-ring 150 mounted thereon and serves to drive the idler delivery roll 140 when in contact with the driven delivery roll 142. The driven roll assembly is moved out of contact with the idler delivery roll 40 by means of a SOL-2 as shown in FIG. 1 which is attached to the assembly by the arm 152 of the solenoid SOL-2. The solenoid SOL-2 actuated through a suitable circuit by a limit switch mounted adjacent the conveyor and actuated by the conveyor 26 at the appropriate time as the paper gripper mechanism approaches the delivery rolls. As the gripper approaches the rear feed out rolls SOL-2 is actuated thereby moving the rear feed out assembly of position to allow the gripper to pass the delivery rolls. After the gripper mechanism has passed the delivery rolls, solenoid SOL-2 is released allowing the driven delivery roll 142 to engage the sheet material and drive the roller 140 to continuously feed the remaining portion of the sheet material from the machine. As the gripper passes the rear feed-out rolls 140-142 the support material is released from the paper by a camming mechanism 160 which moves the rod 90 to the open position. The driven delivery roll 142 then continues to feed material from the machine into an appropriate collecting tray (not shown). The gripper bar will return to the feeding station 28 wherein the cycle can be repeated.

Although the sheet conveyor mechanism and the gripper bar actuating mechanism has been described with reference to the structure of a preferred embodiment disclosed herein, it is not confined to the details set forth.

What is claimed is:

1. A gripping device for transporting copy sheet material including
  - a gripper housing,
  - said gripper housing having mounted thereon and extending along the length thereof spring stock,
  - a rod mounted for rotation on said housing in sliding contact with said spring stock,
  - said rod having a slot therein for receiving copy sheet material,
  - actuating means connected to said rod to cause said rod to rotate to positively grip said sheet material moved into said slot between said rod and said spring stock without crimping or otherwise marring the lead edge thereof.
2. A gripping device for transportation of sheet material including
  - a gripper housing,

said gripper housing having mounted thereon and extending along the length thereof spring stock, a rod mounted for rotation on said housing, said rod having a slot therein for receiving sheet material, actuating means connected to said rod to cause said sheet material to be held between said rod and said spring stock, wherein said spring stock is formed with openings in the front portion thereof, at least one lead edge guide mounted within the housing and extending into any one of said openings formed in said spring stock to guide the leading edge of the sheet material.

3. A device as recited in claim 2 wherein each lead

15

edge guide is arcuate in shape and is movably mounted to engage the rotatable rod.

4. A device as recited in claim 3 wherein each lead edge guide is biased against the rotatable rod for positive engagement therewith.
